UNITED STATES PATENT OFFICE

105,133

DESIGN FOR A SPOON OR ANALOGOUS ARTICLE

Harold E. Nock, Newburyport, Mass., assignor to
Towle Manufacturing Company, Newburyport,
Mass., a corporation of Massachusetts

Application November 5, 1936, Serial No. 65,707

Term of patent 14 years

To all whom it may concern:

Be it known that I, Harold E. Nock, a citizen of the United States, residing at Newburyport, in the county of Essex and Commonwealth of Massachusetts, have invented a new, original, and ornamental Design for a Spoon or Analogous Article, of which the following is a specification, reference being had to the accompanying drawing, forming a part thereof.

In the accompanying drawing Figure 1 is a front elevational view of a spoon showing my new design; and Figs. 2, 3 and 4 are sectional views of the handle taken on the lines 2—2, 3—3 and 4—4, respectively, of the handle shown in Fig. 1.

The dominant feature of my design is the ornamental handle for flatware the dotted lines on the drawing indicating the conventional bowl of a spoon.

The design is delineated as embodied in the handle of a spoon but the design may also be embodied in or applied to the handles of forks, knives, servers and other analogous pieces of flatware which may form a part of a table service of uniform pattern.

I claim:

The ornamental design for a spoon or analogous article, substantially as shown and described,

HAROLD E. NOCK.
